UNITED STATES PATENT OFFICE.

SVEN ROLFSON-SCHMIDT, OF NEW DORP, NEW YORK, ASSIGNOR, BY MESNE ASSIGNMENTS,
TO RICHARD F. WOODWARD, OF HUNTINGTON, NEW YORK.

MEDICATED-SILK PROTECTOR.

No. 880,469.

Specification of Letters Patent.

Patented Feb. 25, 1908.

Application filed June 17, 1905, Serial No. 265,775. Renewed January 18, 1907. Serial No. 352,963.

To all whom it may concern:

Be it known that I, SVEN ROLFSON-SCHMIDT, a citizen of the United States, residing at New Dorp, Staten Island, in the county of Richmond and State of New York, have invented new and useful Improvements in Medicated-Silk Protectors, of which the following is a specification.

One of the most dreaded and at the same time annoying diseases common among women is the so-called "whites". Medical authorities have given the subject of this disease deep thought, and have encouraged physicians to devote their time and study to the

15 perfection of a remedy.

The object of my invention is to effect a permanent cure of female diseases of the character indicated.

With the foregoing and other objects in view which will appear as the description proceeds, the invention resides in the medical device hereinafter described and claimed as a practical embodiment thereof.

In the accompanying drawing forming 25 part of this specification,—Figure 1 is a sectional view through the womb of a woman, showing the method of applying the device of this invention. Fig. 2 is a rear elevation of the device. Fig. 3 is a front elevation 30 thereof. Fig. 4 is a sectional view. Fig. 5 is a side elevation of a modified form of the invention.

As shown in the drawing, the device of this invention comprises a plurality of threads 35 1 which consist of any suitable soft material such for example as silk. The threads 1 are bound together intermediate their ends in any suitable manner as indicated at 2. On what I shall for convenience term the rear 40 side of the binding 2, the threads 1 are spread radially into the formation of a wheel, so as to produce the effect of a sun with rays of light radiating therefrom as indicated in Fig. 2. The radial or sun formation at the 45 rear end of the device is adapted to contact with the posterior portion of the vagina surrounding the mouth of the womb as indicated at 3. At the forward end of the device, the threads 1 are spread radially into a star 50 formation as indicated in Fig. 3. The object in thus forming the forward ends of the threads 1 into a star formation is, that when the device is inserted into the vagina as indicated in Fig. 1, the forward end of the device 55 will be tapered so as not to fill the entire

mouth of the vagina and yet contact therewith.

The threads 1 of the device are permanently impregnated with any suitable antiseptic and curative chemicals. By reason of the 60 fact that the device is formed of soft silken threads, it causes no discomfort to the wearer, and as the threads adhere closely to the affected parts, it serves not only to absorb the excretions but also to treat parts 65 constantly with the antiseptic and curative chemicals with which the threads are impregnated, and a permanent cure of the disease is effected in time.

In order to insure that the sun formation 70 indicated in Fig. 2 will adhere closely to the affected posterior portion of the vagina, it is preferable to surround the intermediate portion of the threads 1 with a confining means to limit the spread of the threads, as, for example, with a soft tube 4 constructed of any 75 suitable material such for example as rubber. The tube 4 at its outer end is preferably formed with a small flared portion as indicated at 5, and at its inner end with a 80 large flared portion as indicated at 6. When inserting the device into the vagina, the large flared portion 6 assumes the position indicated by the dotted lines in Fig. 4, and when the device has been inserted completely, the flared portion 6 assumes the position shown in full lines so as to cause the sun formation shown in Fig. 2, to cover the posterior portion of the womb.

It will be understood that the improved 90 device of this invention is used without the tube 4, when the vagina is small.

The device of this invention is peculiarly effective in the cure of female diseases by reason of the fact that it is absorbent; that 95 it is composed particularly of a natural or animal product such as silk, which will not injuriously affect the internal human organs by contact; that it is impregnated with specially prepared chemicals which soothe 100 and heal the affected parts and which are sufficiently permanent to permit the device to be washed whenever necessary; that the silken threads are strong, and yet softer than the mucous membrane; and that after 105 insertion into the vagina, the device spreads and thus covers practically all the affected parts of the womb.

Changes in the precise embodiment of invention illustrated and described may be 110

made within the scope of the following claims without departing from the spirit of the invention or sacrificing any of its advantages.

Having thus described the invention what is claimed as new is:—

1. A medical device comprising a plurality of threads, and means for confining the threads at a point intermediate their ends, the threads projecting through said means and extending beyond the ends thereof, the respective ends of the confining means being of different diameters to correspondingly limit the spread of the threads.
2. A medical device comprising a plurality of soft threads, and a soft tube surrounding said threads intermediate their ends, said tube being formed with flared

ends, and said threads being spread into radial formations at the ends of said tube.

3. A medical device comprising a mass of absorbent material, and an integral means for confining said material at a point intermediate its ends, said material projecting beyond said means, the respective ends of the confining means being of different diameters to correspondingly limit the spread of the absorbent material.

In testimony whereof, I affixed my signature in presence of two witnesses.

SVEN ROLFSON-SCHMIDT.
